AUTOMATIC TRAIN CONTROL

Refiled for abandoned application Serial No. 650,244, filed July 9, 1923. This application filed July 17, 1928.
Serial No. 293,342.

This invention relates to automatic railway signalling, particularly to systems especially applicable for railways having sections of track upon which trains are operated in both directions and more especially to such systems in which there is a manual control of the signalling means.

I have heretofore proposed a system of train control including means whereby an operator can instantly change the signals on a section of track for one direction of train movement to the opposite direction if there is no train in the section, the section being divided into a number of blocks so as to facilitate following train movements.

In this invention, the signals on any number of sections of track, which are subdivided into several blocks, may be changed from a central point such as a dispatcher's office, interlocking tower or way station by an operator, if there is no train in the section. That is, an operator having a plurality of sections of track under his control may set up the signal protection so as to provide for an east bound movement of trains but if there is no train in the section, he may instantly change the signal protection for the section so as to provide for a west bound movement of trains.

In order that the operator may intelligently govern train movements with the least delay, means are provided to automatically indicate or record the movements of trains at his office so that he has knowledge of the location and progress of all trains under his jurisdiction.

A further object of the invention is to prevent the operator from setting up proceed signals over a section of track for both an east bound and for a west bound movement at the same time and to prevent him from changing from one direction to the opposite as long as there is a train in the section.

Other objects and advantages will appear as the description of the particular physical embodiment of the invention and desirable modifications thereof selected to illustrate the invention progresses and the novel features will be pointed out in the appended claims.

In describing the invention in detail, ref-

erence is had to the accompanying drawings wherein I have illustrated a preferred physical embodiment of my invention and wherein like characters of reference designate corresponding parts throughout the several views and in which:

Fig. 1 is a schematic representation of the apparatus and circuits in the dispatcher's office and along the track embodying my invention.

Fig. 2 is a schematic representation of the apparatus and circuits on the locomotive or car.

Fig. 3 is a modification of Fig. 1, and shows a schematic representation of part of the apparatus in the dispatcher's office and along the track by which fixed signals are displayed instead of cab signals.

Fig. 1 shows a single track consisting of rails 1 and 2. Rail 1 is electrically continuous. Rail 2 is divided into sections by means of insulating joints as 3, thus dividing the track into block sections as A, B, C, D, E, F and G. In blocks B and F are shown sidings as 4 where trains can meet and pass each other. Since the apparatus and circuits for each single track section between passing sidings are identical, only one complete single track section has been shown in Fig. 1, but the dispatcher's control and the recording of train movements has been shown for three single track sections, thus a switch as 5 in the dispatcher's office, interlocking tower or way station controls the signals for a section west of block B. A switch as 6 controls the signals of the section between blocks B and F and a switch as 7, controls the signals of a section east of block F. At the clearance point of the sidings insulating joints as 3 electrically separate the straight portions of the sidings from the main track in a manner and for a purpose well known to those skilled in the art.

Each block is provided with a track circuit, a track battery as 8 being located at one end of each block and track relays as a, b, c, d, e, f and g near the other end of the block, constituting with their connections to the rails, a track circuit well known to those skilled in the art. Track relays as a, b, d, 100

e and *f* control two armatures as 9 and 10 and track relays *c* and *g* control three armatures as 9, 10 and 11. When there is no train in the block, the track relay for the block is energized and its armatures through their respective front contacts, control certain signals; and when there is a train in the block, its track relay is deenergized and its armatures will close certain back contacts for the purpose of locking switches 5, 6 and 7 and making a record of train movements as will be described in more detail hereinafter.

Adjacent to the track are located groups of train control rails as A12 and A13, B12 and B13, C12 and C13, D12 and D13, E12 and E13, F12 and F13, and G12 and G13. The letter prefix, as "B", to train control rails 12 and 13 indicates that these train control rails are located in a block of the same letter designation. Train control rails 12 and 13 are on the right hand side of the center line of the track, looking east, and control east bound movements into a block and a similar group of train control rails on the opposite side of the track, that is on the right hand side of the center line of the track, looking west, control west bound movements into a block. These west bound train control rails have been designated as A14 and A15, B14 and B15, C14 and C15, D14 and D15, E14 and E15, F14 and F15, and G14 and G15. In each group of train control rails one is the home train control rail and located near the entrance to a new block and the other is a distant train control rail and located approximately the braking distance from the home rail. Thus train control rail 13 is the home train control rail for an east bound train movement and train control rail 14 is the home train control rail for a west bound movement and train control rail 12 is the distant train control rail for an east bound train movement and train control rail 15 is the distant train control rail for a west bound movement.

When east bound train control rails are energized with direct current, a clear signal is displayed on an east bound locomotive and when train control rails are deenergized, a danger signal is displayed. When the west bound train control rails are energized with alternating current, a clear signal is displayed on a west bound locomotive and when these rails are deenergized, a danger signal is displayed. The east bound train control rails are energized with direct current from a battery as 16 preferably located in the dispatcher's office by a certain position of manually operable switches 5, 6 and 7 and the west bound train control rails are energized with alternating current from an alternating current source as 17, by certain other positions of the manually operable switches 5, 6 and 7, and while the circuit from battery 16 and alternating current source 17 is partially com-

mon to both sources of energy, the east bound train control rails can only be energized with direct current by reason of the insertion in the circuit of an impedance coil as 18 which prevents the flow of alternating current to east bound train control rails and the west bound train control rails can only be energized with alternating current by reason of the insertion on the circuits of a condenser as 19 which prevents the flow of direct current to the west bound train control rails. Thus when switches 5, 6 or 7 are in position to energize train control rails with direct current, only the east bound train control rails are so energized while the west bound train control rails are deenergized, and if switches 5, 6 or 7 are in the position to energize train control rails with alternating current, only the west bound train control rails are so energized while the east bound train control rails are deenergized.

If switches 5, 6 or 7 are in a position to give a clear signal to either an east bound or a west bound train, the train control rails will be deprived of the selected energy, if the block ahead is occupied, since the circuit from the dispatcher's office is broken through the corresponding track relay of the occupied block.

I will now describe how the east bound train control rails may be energized with direct current. From battery 16 in the dispatcher's office and since manually operable switch 6 controls the section between blocks A and F, representing a complete section between passing sidings, I will trace the circuits through switch 6.

When switch 6 is in the position as shown in Fig. 1, making contact with spring contact 20, the east bound train control rails A12 and A13, B12 and B13, C12 and C13 and D12 and D13 are all energized with direct current, thus conditioned to give a clear signal to an east bound locomotive if there is no train in the block ahead. The train control rails A12 and A13 are energized through the following circuit:—From positive pole of battery 16, wire 22, impedance coil 23, bus 24, wire 25, spring contact 20, switch 6, shaft 26, wire 27, relay 28, wires 29, 30 and 31, armature 11 of track relay *c*, front contact 34, wire 35, front contact 33, of track relay *b*, armature 10, wire 36, impedance 18, wire 37, to train control rails A13 and A12 and thence through a circuit on the locomotive to be described hereinafter, to track rail 1 and thence through wires 38 and 39 to negative pole of battery 16. Similarly train control rails B12 and B13 are energized through a branch circuit as follows:—From positive pole of battery 16, wire 22, impedance 23, bus 24, wire 25, spring contact 20, switch 6, shaft 26, wire 27, relay 28, wires 29, 30 and 40, armature 10, of track relay *c*, front contact 33, wire 41, impedance 18, wire 42, to train control rails

B13 and B12 and thence the circuit is completed to the negative pole of battery 16 as hereinbefore described. Similarly train control rails C12 and C13 are energized 5 through a branch circuit as follows: From positive pole of battery 16, wire 22, impedance 23, bus 24, wire 25, spring contact 20, switch 6, shaft 26, wire 27, relay 28, wires 29, 43, 44 and 45, armature 10 of track relay *d*, front contact 33, wire 46, impedance 18, wire 47, to train control rails C13 and C12 and thence the circuit is completed to the negative pole of battery 16 as hereinbefore described. Similarly train control rails D12 10 and D13 are energized through the branch circuit as follows:—From positive pole of battery 16, wire 22, impedance 23, bus 24, wire 25, spring contact 20, switch 6, shaft 26, wire 27, relay 28, wires 29, 43, 48, 49 and 50, armature 10 of track relay *e*, contact 33, wire 51, impedance 18, wire 52, to train control rails D13 and D12 and thence the circuit is completed to negative pole of battery 16 as hereinbefore described. It will be noted that 15 the circuit to train control rails A12 and A13 is taken through the armatures of both track relays *b* and *c* so that if either of these blocks are occupied, train control rails A12 and A13 will be deenergized and the purpose for this 20 will be described more fully hereinafter. With switch 6 in contact with spring contact 21, the west bound train control rails are energized with direct current but the east bound train control rails controlled by switch 6 are 25 deenergized, since the direct current cannot reach these train control rails by reason of the insertion of condensers 19 in the circuit. 30 When switch 6 is placed in the position opposite to that shown in Fig. 1, so as to make 35 contact with spring contact 21, the west bound train control rails G14 and G15, F14 and F15, E14 and E15, D14 and D15, are all energized with alternating current, thus 40 conditioned to give a clear signal to a west bound locomotive if there is no train in the 45 block ahead. The train control rails G14 and G15 are energized through the following circuit: from alternating current source 17, wire 53, condenser 54, bus 55, wire 56, spring 50 contact 21, switch 6, shaft 26, wire 27, relay 28, wires 29, 43, 48, 57, 58 and 59, armature 9 of track relay *f*, front contact 32, wire 60, condenser 19, and wire 61 to train control 55 rails G14 and G15 and thence through a circuit on the locomotive to be described herein- 60 after to track rail 1 and thence through wires 38 and 62 to alternating current source 17. Similarly train control rails F14 and F15 are energized through a branch circuit as fol- 65 lows: From alternating current source 17, wire 53, condenser 54, bus 55, wire 56, spring contact 21, switch 6, shaft 26, wire 27, relay 28, wires 29, 43, 48, 49 and 63, armature 9 of track relay *e*, front contact 32, wire 64, condenser 19, wire 65, to train control rails F14 70 and F15 and thence the circuit is completed to alternating current source 17 as hereinbefore described. Similarly train control rails E14 and E15 are energized through the following circuit: From alternating current source 17, wire 53, condenser 54, bus 55, wire 56, spring contact 21, switch 6, shaft 26, wire 27, relay 28, wires 29, 43, 44 and 66, armature 9 of track relay *d*, front contact 32, wire 67, condenser 19, wire 68, to train control rails E14 and E15 and thence the circuit is completed to alternating current source 17 as hereinbefore described. Similarly train control rails D14 and D15 are energized 75 through the following branch circuit: From alternating current source 17, wire 53, condenser 54, bus 55, wire 56, spring contact 21, switch 6, shaft 26, wire 27, relay 28, wires 29, 30 and 69, armature 9 of track relay *c*, front contact 32, wire 70, condenser 19, wire 71, train control rails D14 and D15 and thence the circuit is completed to alternating current source 17 as hereinbefore described. With switch 6 in contact with spring contact 80 21, the west bound train control rails are energized with alternating current but the east bound train control rails controlled by switch 6 are deenergized since the alternating current cannot reach these train control rails by reason of the insertion of impedances 85 18 in the circuit. 90 When switch 6 is in the vertical position so as not to make contact with spring contact 20 or 21, both east and west bound train control rails are deenergized and thus conditioned to display a danger signal to both an east bound and a west bound locomotive as will be more fully described hereinafter. 95 It will thus be seen that the dispatcher 100 may condition the train control rails governing the single track section between passing sidings for an east bound train movement, for a west bound train movement or he may condition them to display a danger signal to both east and west bound trains. In addition 105 to the dispatcher's manual control of the electrical conditions of the train control rails, automatic control is also provided by means of a track circuit. Assuming that there is no 110 train in any of the blocks between B and E, and the dispatcher has set up an east bound train movement by placing switch 6 in contact with spring contact 20, and a train receives a clear signal at train control rail B13 115 and proceeds into block C; as soon as the train has entered block C, the current from track battery 8 of block C is short circuited through the wheels and axles of the train and therefore track relay *c* becomes sufficiently 120 deenergized so that its armatures will drop away from the front contacts. When this occurs train control rails B12 and B13 become deenergized since the circuit is now broken by armature 10 of track relay *c* dropping away from front contact 33. As soon 125 130

however as the train has left block C and entered block D, track relay *c* again becomes energized thus again closing the circuit to train control rails B12 and B13 and a second train may proceed eastward with a clear signal. It will therefore be seen that a train which proceeds over the road automatically protects itself in the rear, so that a following train will automatically receive a danger signal when it arrives within braking distance of a train ahead, occupying the block ahead. The same automatic rear end protection by means of a track circuit is also provided for west bound movements. For instance, a west bound train entering block E will deenergize track relay *e*, thus breaking the circuit at front contact 32 of track relay *e* and deenergizing west bound train control rails F14 and F15. As soon, however, as this train has left block E, train control rails F14 and F15 are again energized thus permitting a following train to proceed with a clear signal.

The object of taking the circuit to train control rails A12 and A13 through both track relays *b* and *c* and the circuit through train control rails E12 and E13 through both track relays *f* and *g* is as follows:—If the dispatcher has placed switch 6 in contact with spring contact 20, thus setting up an east bound movement of a train from blocks B to E, and also placed switch 7 in contact with spring contact 21, thus setting up a west bound movement for a train running in the single track section east of block G, the two trains will have to meet and pass each other at the siding in block F. If now the east bound train entered block E approximately at the same time that the west bound train entered block G, each train will automatically receive a danger signal by reason of the track circuit control before reaching block F and this will give the train ample distance to slow down or stop until one of the trains has taken the siding. This arrangement is desirable if block F and the siding are relatively short. While this arrangement shows the preferred form, it is not absolutely necessary, particularly if block F and its siding are relatively long. The arrangement of taking the circuit to the train control rails through two track relays can also be obviated by placing the distant train control rails F12 and F15 a sufficient distance back to give the engineer ample warning to stop for the meet.

The system is so arranged that when the dispatcher has set up an east bound movement from block B to block E by placing switch 6 in contact with spring contact 20, as soon as the train has entered block C, after receiving a clear signal at train control rail B13, switch 6 is automatically locked in the position it is in so that it cannot be moved by the dispatcher and the switch remains locked until the train has passed out of

block E. This is accomplished in the following manner:—Switches 5, 6 and 7 are rotatable on the shaft 27; secured to this shaft is a disk as 72. In the periphery of this disk are two notches as 73 and 74. The armature as 75 of relay 28 is hinged at 76. At the other end of armature 75 is a detent as 77 so positioned that when switch 6 is in contact with spring contact 20, detent 77 will be in alignment with notch 73 and when switch 6 is in contact with spring contact 21, detent 77 is in alignment with notch 74. Relay 28 is of such design that when it is energized with either direct current or alternating current, it will attract armature 75 and detent 77 and if detent 77 is in alignment with either of notches 73 or 74, it will engage one of the notches, thus preventing the switch from being turned from the position it is in as long as relay 28 is energized. When relay 28 is not energized, a spring as 78 pulls detent 77 out of engagement with the notches in disk 72.

When switch 6 is in contact with spring contact 20, relay 28 is energized, and thus the switch is locked as long as there is a train in blocks C or D. When block C is occupied relay 28 is energized through the following circuit: from positive pole of battery 16, wire 22, impedance 23, bus 24, wire 25, spring contact 20, switch 6, shaft 26, wire 27, relay 28, wires 29, 30 and 31, armature 11 of track relay *c*, back contact 79, and wire 80, to track rail 1 and thence through wires 38 and 39 to negative pole of battery 16. When block D is occupied relay 28 is energized through the following circuit: from positive pole of battery 16, wire 22, impedance 23, bus 24, wire 25, spring contact 20, switch 6, shaft 26, wire 27, relay 28, wires 29, 43, 44 and 45, armature 10 of track relay *d* back contact 79, and wire 81 to track rail 1, and thence by wires 38 and 39 to the negative pole of battery 16. When block E is occupied relay 28 is energized through the following circuit: from positive pole of battery 16, wire 22, impedance 23, bus 24, wire 25, spring contact 20, switch 6, shaft 26, wire 27, relay 28, wires 29, 43, 48, 49 and 50, armature 10 of track relay *e*, back contact 79, wire 82 to track rail 1 and thence by wires 38 and 39 to negative pole of battery 16. It will thus be seen that as long as an east bound train occupies either blocks C, D, or E, detent 77 engages notch 73, thus locking switch 6 in the position it is in.

When switch 6 is in contact with spring contact 21, relay 28 is energized as long as there is a west bound train in blocks E, D, or C. When block E is occupied relay 28 is energized through the following circuit: from alternating current source 17, wire 53, condenser 54, bus 55, wire 56, spring contact 21, switch 6, shaft 26, wire 27, relay 28, wires 29, 43, 48, 49 and 50, armature 10 of track re-

lay *e*, back contact 79, wire 82, track rail 1, and wires 38 and 62 to alternating current source 17. When block D is occupied relay 28 is energized through the following circuit: 5 from alternating current source 17, wire 53, condenser 54, bus 55, wire 56, spring contact 21, switch 6, shaft 26, wire 27, relay 28, wires 29, 43, 44 and 45, armature 10 of track relay *d*, back contact 79, wire 81, track rail 1, wires 10 38 and 62 to alternating current source 17. When block C is occupied, relay 28 is energized through the following circuit: from alternating current source 17, wire 52, condenser 54, bus 55, wire 56, spring contact 21, 15 switch 6, shaft 26, wire 27, relay 28, wires 29, 30 and 31, armature 11 of track relay *e*, back contact 79, wire 80, track rail 1, and wires 38 and 62 to alternating current source 17. 20 It will be thus be seen that when the dispatcher has set up an east bound movement from block B to block E and a train has accepted a clear or proceed signal and has entered block C, the dispatcher is unable to change the position of switch 6 until the train has left block E, and when the dispatcher has set up a west bound movement from block F to block C and a train has accepted a clear or proceed signal and has entered block D, 25 the dispatcher is unable to change the position of switch 6 until the train has left block C. In other words the dispatcher is unable to give a proceed signal to both an east bound train and a west bound train at the same time 30 between two points where trains may pass each other.

It will be noted that track relays *b* and *f* have not been provided with a back contact. This back contact has been omitted in the 40 preferred form so that switches 5, 6 and 7 will be unlocked as soon as a train has left the single track portion of the railroad and has entered a siding block such as B or F. It is desirable in the preferred form to give the 45 dispatcher full liberty in placing switches in the positions desired as soon as the train has reached the main track or the siding of block B or F.

I will now describe the apparatus and circuits on the locomotive capable of displaying a clear signal to an east bound train when passing a train control rail which is energized with direct current and displaying a clear signal to a west bound train when passing 50 a train control rail which is energized with alternating current and displaying a danger signal to both an east and west bound train when passing a train control rail which is deenergized, and also how these signals are continued after the locomotive has passed the train control rail.

In Fig. 2, is shown a device represented as a lamp which is designated as No. 1, and another also represented as a lamp designated as No. 2. While these devices are shown as

70 lamps and are signals, they may equally as well represent an electromagnetic device to which motion is given depending upon whether the circuit is energized or deenergized and such electromagnetic devices may be used for other purposes than, or in addition to, the display of signals to the engineer, such as, is well known in the art, the proper control of speed control devices or electropneumatic air valves or both. 75

In Fig. 2, is shown an electric contact shoe 83 so positioned on the locomotive as to make contact with train control rails. The contact shoe is hinged at 84. The train control rails are inclined at the ends so as to 80 form a ramp in the usual manner such as is shown in my prior Patent No. 1,140,623, granted May 25, 1915. When the contact shoe slides along this ramp the shoe is tilted so as to break contact at contacts 85, 86 and 87. When the contact shoe leaves the other end of train control rail, spring 88 forces the contact shoe to the normal position thus again closing the contacts 85, 86 and 87.

The locomotive also carries a direct current 90 relay as 89 and an alternating current relay as 90 with its companion direct current coil as 91 and two batteries as 92 and 93. Direct current relay 89 controls two armatures as 94 and 95 and when energized, armature 94 will close two front contacts as 96 and 97 and when relay 89 is deenergized armature 95 will close back contact as 98. Alternating current relay 90 controls two armatures 99 and 100 and when the relay is energized 100 armature 99 will close front contact 101 and armature 100 will close front contact 102 and when the relay is deenergized armature 100 will close back contact 103.

When the contact shoe 83 is passing an east bound train control rail such as for instance B13 and the train control rail is energized with direct current, current is supplied to relay 89 from battery 16 in the dispatcher's office through the following circuit: from positive pole of battery 16, wire 22, impedance 23, bus 24, wire 25, spring contact 20, switch 6, shaft 26, wire 27, relay 28, wires 29, 30 and 40, armature 10 of track relay *e*, front contact 33, wire 41, impedance 18, wire 42, train control rail B13, contact shoe 83, wires 104 and 105, impedance 106, wire 107, relay 89, wires 108, 109, 110, 111 and 112, resistance 113, wire 114, axle 115, wheel 116, track rail 1, and wires 38 and 39, to negative pole of battery 16. With relay 89 energized its armature 94 will close front contacts 96 and 97 and a circuit is established through signal No. 1, the clear signal, as follows: from positive pole of battery 92, wires 117 and 118, armature 94, front contact 97, wires 119 and 120, signal No. 1, wires 121, 110 and 122, to the negative pole of battery 92. When the contact shoe 83 leaves the other end of the train control rail, contacts 85, 86 and 87 are 130

again closed and a stick circuit is established through relay 89 as follows: from positive pole of battery 92, wires 117 and 118, armature 94, front contact 96, wire 123, contact 85, contact shoe 83, wires 104 and 105, impedance 106, wire 107, relay 89, wires 108, 109 and 122 to negative pole of battery 92. Thus signal No. 1, the clear signal, is continued after contact shoe 83 has left the train control rail.

Assuming now that train control rail B13 is deenergized by reason of the switch 6 being in contact with contact spring 21 or by reason of switch 6 being open or by reason of there being a train in block C, then when the east bound train passes train control rail B13, the stick circuit heretofore described is broken by reason of the breaking of contact 85 and armatures 94 and 95 will assume the deenergized position since train control rail B13 is deenergized, relay 90 will also be deenergized and its armatures 99 and 100 will assume the deenergized position. Under these conditions a circuit is established through signal No. 2, the danger signal, as follows: from positive pole of battery 92, wires 117 and 124, armature 100, back contact 103, wire 125, armature 95, back contact 98, wire 126, signal No. 2, wires 127, 111, 110 and 122, to negative pole of battery 92. If the train under these conditions proceeds, and contact shoe 83 leaves the other end of the train control rail, signal No. 2 will be continued until a train control rail is reached which is energized. After contact shoe 83 leaves train control rail, contact 85 is again closed but the stick circuit hereinbefore described is now open at front contact 96 and relay 89 will remain deenergized.

Assuming now that the single track section between F and C is set up for a west bound movement by reason of switch 6 being in contact with spring contact 21, then all of the train control rails between blocks F and block C will be energized with alternating current and when a west bound train is passing, say, train control rail F14 relay 89 will be deenergized but relay 90 will now be energized through the following circuit: from alternating current source 17 in the dispatcher's office wire 53, condenser 54, bus 55, wire 56, spring contact 21, switch 6, shaft 26, wire 27, relay 28, wires 29, 43, 48, 49 and 63, armature 9 of track relay e front contact 32, wire 64, condenser 19, wire 65, train control rail F14, contact shoe 83, wires 104 and 128, condenser 129, wire 130, alternating current relay 90, wires 131, 109, 110, 111 and 112, resistance 113, wire 114, axle 115, wheel 116, track rail 1, wires 38 and 62, to alternating current source 17. With relay 90 thus energized, its armatures 99 and 100 will close front contacts 101 and 102, and a circuit is established through signal No. 1, the clear signal, as follows: from

positive pole of battery 92, wires 117 and 124, armature 100, front contact 102, wires 132 and 120, signal No. 1, and wires 121, 110 and 122 to the negative pole of battery 92. When the contact shoe 83 leaves the other end of the train control rail a stick circuit is established through the holding coil 91 of relay 90 as follows: from positive pole of battery 93, wire 133, coil 91, wire 134, contact 87, metallic plate 135, contact 86, wire 136, front contact 101, armature 99, and wire 137 to the negative pole of battery 93. Metallic contact plate 135, is attached to contact shoe 83 but insulated therefrom and when the contact shoe slides along the ramp in approaching a train control rail contacts 86 and 87 are broken, thus signal No. 1 is continued after leaving a train control rail until the next train control rail is reached.

Assuming that train control rail F14 is deenergized by reason of switch 6 being in contact with spring contact 20 or by reason of switch 6 being open or by reason of there being a train in block E, then when the west bound train passes train control rail F14, the stick circuit heretofore described is broken by reason of the breaking of contacts 86 and 87. Both coils of relay 90 will be deenergized and armatures 99 and 100 will assume the deenergized position. Relay 89 is also deenergized and its armature 94 and 95 will assume the deenergized position. Under these conditions a circuit is established through signal No. 2, the danger signal, as heretofore described and if the train proceeds under these conditions, signal No. 2 will be continued until a train control rail is reached which is energized.

It is evident that when the switch 6 is in contact with spring contact 20, the normal position for an east bound movement, from block B to block E, relay 89 on the locomotive will be energized when passing any other train control rail in the section so controlled through the several circuits hereinbefore described if there is no train in the block ahead and thus the clear signal is repeated at each east bound train control rail and similarly when switch 6 is in contact with spring contact 21, the normal position for a west bound movement from block F to block C, relay 90 will be energized when passing any other train control rail through the several circuits heretofore described, if there is no train in the block ahead, and thus the clear signal is repeated at each west bound train control rail. If however, either an east bound train or a west bound train approaches within one block of the train ahead, the train control rail governing the entrance into the occupied block, will be deenergized automatically by reason of the track circuit control and a danger signal will be displayed.

Impedances are inserted in the circuits in which they are inserted to prevent the flow of

alternating current in the circuit and condensers are inserted in the circuits in which they are inserted to prevent the flow of direct current through the circuit. Resistance 113 is inserted in the cab circuit for the following purpose: When there is a train in blocks C, D or E, current is flowing through relay 28 in the dispatcher's office thus locking switch 6 in the position it is in, as hereinbefore described. When the contact shoe 83 on the locomotive is passing an energized train control rail current is also flowing through relay 28, but by reason of the combined resistances of relays 89 or 90 and resistance 113 there is not sufficient current flowing through relay 28 to attract its armature 75 against the tension of spring 78, therefore, a train passing a train control rail will not lock switch 6. For instance, it is desirable when a train is in block B that the switches governing the adjacent stretches of track be unlocked and it is possible that a contact shoe on a locomotive may be in contact with either train control rails B12 or B13 or B14 or B15 and this would lock the switches if the current flow is not reduced as arranged by the introduction of the necessary resistance in the cab circuit.

I will now describe the means by which an indication or a record is made in the dispatcher's office of the movement of trains. In the dispatcher's office is a suitably mounted record sheet as 138 driven by a roller as 139 which in turn is driven by a shaft as 140. Shaft 140 receives motion through ratchet wheel 141. A pawl as 142 is pivotally attached to armature 143 of electromagnet 144, the armature being hinged at 145. When electromagnet 144 is periodically energized, motion is given to ratchet wheel 141 by pawl 142. A spring as 146 normally pulls armature 143 and pawl 142 to the right when electromagnet 144 is not energized. Electromagnet 144 is connected by wire 147 to a make and break device as 148 which make and break device is periodically operated by a clock as 149. This may well be of the form shown in my prior Patent 1,203,146, granted October 21, 1916. When the make and break device is closed the electro-magnet 144 is energized through the following circuit: from battery 150, wires 151 and 152, electromagnet 144, wire 147, make and break device 148, wire 153 and 154, to opposite pole of battery 150. The make and break device 148 is operated say every five seconds so as to give a slow and uniform movement to record sheet 138 through ratchet wheel 141 and pawl 142.

The record sheet 138 is transversely divided into sections as 155, 156 and 157, each section representing a section of single track between sidings or other points where trains may pass each other. Longitudinally the record sheet is divided into time lines such as 1 a. m., each one of the lines representing a one minute interval. It will thus be seen that longitudi-

nally the record sheet assumes a constantly changing position during the 24 hours of the day.

Adjacent to the record sheet are located perforating magnets as 158 and 159, two for each section of single track, these perforating magnets control armatures as 160. Pivotaly attached to armatures 160 are perforating needles as 161 so positioned adjacent to the record sheet that when a perforating magnet is energized, a perforation is made in the record sheet.

Perforating magnet 158 records east bound train movements through blocks C, D and E and perforating magnet 159 records west bound train movements through blocks E, D and C. As hereinbefore described, when blocks C, D or E are occupied by either an east bound or west bound train, relay 28 is energized and its armature 75 is in the energized position. Attached to armature 75 but insulated therefrom is a contact plate as 162 and when armature 75 is in the energized position, this contact plate makes contact with contacts 163 and 164, thus closing the circuit through the perforating magnets at this point. Also attached to switch 6 are metallic wedges 165 and 166 but insulated therefrom. When switch 6 is set up for an east bound train movement thus making contact with spring contact 20, metallic wedge 165 makes electrical contact with spring contact 167 and 168 thus closing the circuit through perforating magnet 158 at this point. The circuit through perforating magnet 158 is as follows: from battery 150, wires 151 and 169, contact 170, metallic plate 171, contact 172, bus 173, wire 174, perforating magnet 158, wire 175, spring contact 167, metallic wedge 165, spring contact 168, wire 176, contact 163, metallic plate 162, contact 164, wires 177 and 154, to the other side of battery 150.

When switch 6 is set up for a west bound train movement, thus making contact with spring contact 21, metallic wedge 166 makes electrical contact with spring contacts 178 and 179 and thus closing the circuit through perforating magnets 159 at this point. The circuit through perforating magnet 159 is as follows: from battery 150, wires 151 and 169, contact 170, metallic plate 171, contact 172, bus 173, wire 174, perforating magnet 159, wire 180, contact spring 178, metallic wedge 166, spring contact 179, wires 181 and 176, contact 163, metallic plate 162, contact 164, wires 177 and 154 to the other side of battery 150.

It will be noted that the circuits through the perforating magnets are taken through a circuit breaking device as 171 so that these circuits are periodically made and broken. This circuit breaking device operates as follows: metallic contact plate 171, is attached to armature 143, but insulated therefrom. Every time electromagnet 144 is energized

which as hereinbefore stated is say every five seconds the contacts 170 and 172 are closed through metallic plate 171, when magnet 144 is deenergized, armature 143 is pulled to the right by spring 146 and the circuit through the perforating magnet is broken. By reason of this periodic breaking of the circuit, a continuous perforation is made on the record sheet as long as the section of single track consisting of blocks C, D and E is occupied by a train. Thus when an east bound train leaves block B perforating magnet 158 will start to perforate in section 153 of the record sheet as soon as the train has entered block C, and will continue to perforate until the train has left block E, thus recording the exact time when the train entered the single track section and also the length of time the train remained in the single track section. Similarly a west bound train will record its movement through perforating magnet 159. A dispatcher having a number of track sections under his control thus knows what progress the trains are making under his supervision and can direct the train movements by properly positioning the manually operable switches with the greatest dispatch, for instance, by the accurate knowledge of the location of trains on his division, he decides that block B is the most suitable place for an east bound train to pass a west bound train, under these conditions switch 5 will be placed in the east bound position thus making contact with spring contact 20. This will permit the east bound train to proceed with a clear signal up to the distant train control rail A12, at which point the clear signal will change to danger. Switch 6 will be placed in the west bound position thus making contact with spring contact 21 and the west bound train will proceed with a clear signal until train control rail C15 is reached, at which point the danger signal will be shown and the train would thus be advised to prepare to meet a train. When an east bound train is traveling toward block B perforating magnet 158 in the section 157 of the record sheet would continue to perforate, but this perforation will automatically cease as soon as the east bound train has left block A and entered block B or the siding at block B. Thus the dispatcher will be fully advised of the arrival of the east bound train at B. Similarly the west bound train would make a record of its progress by perforating magnet 159 in the section 156 of the record sheet and perforating magnet 159 will continue to perforate as long as the train is in either blocks E, D or C. As soon however, as the west bound train has cleared block C perforating magnet 159 of section 156 will cease to perforate and thus the dispatcher is advised that the west bound train has arrived at B. With this knowledge the

dispatcher can intelligently change the position of the switches so as to facilitate the movement of trains with the greatest dispatch.

The modification shown in Fig. 3, is identical with Fig. 1, insofar as circuits for the indicating or recording means are concerned and the difference consists in substituting fixed signals for the train control rail necessary for cab signals. The several blocks, track batteries and track relays and track relay armatures are identical as are also circuits from the battery 16 and the alternating current source 17 in the dispatcher's office, through the several positions of switches 5, 6 and 7 and the armatures of track relays, but instead of two train control rails being shown for each direction for each block, relays 182 and 183 are substituted for the control of fixed signals. Relay 182 is a direct current relay responding only to direct current and controls the fixed signals for east bound train movements while relay 183 is an alternating current relay responding only to alternating current and controls the fixed signals for west bound train movements. These relays may control both home and distant fixed signals in the manner well known to those skilled in the art, or may be considered the signals. When a relay is energized, a clear signal is displayed and when it is deenergized, a danger signal is displayed.

I will now trace the circuits through direct current relay 182 which controls the east bound signal into block D. When the dispatcher has placed switch 6 in contact with terminal 20 thus authorizing an east bound train movement, from block B to block E, the circuit is closed through relay 182 governing the entrance to block D as follows: from positive pole of battery 16 in the dispatcher's office, wire 22, impedance 23, bus 24, wire 25, spring contact 20, switch 6, shaft 26, wire 27, relay 28, wires 29, 43, 44 and 45, armature 10 of track relay d, front contact 33, wire 46, resistance 184, wire 181, impedance 186, direct current relay 182, wire 187, track rail 1, and wires 38 and 39, to negative pole of battery 16. With current flowing in this circuit, relay 182 is energized, thus displaying a clear signal for an east bound movement into block D. If however there is a train in block D track relay d becomes deenergized, and its armature 10 will break away from front contact 33 resulting in relay 182 being deenergized and thus displaying a danger signal.

The circuit through alternating current relay 183 which governs the west bound signals into block C is as follows: from alternating current source 17, wire 53, condenser 54, bus 55, wire 56, spring contact 21, switch 6, shaft 26, wire 27, relay 28, wires 29, 30 and 69, armature 9 of track relay, front contact 32, wire 70, resistance 188, wire 189, condenser 130

190, wire 191, alternating current relay 183, wire 192, track rail 1 and wires 38 and 62 to alternating current source 17. With current flowing in this circuit relay 183 is energized 5 thus displaying a clear signal for a west bound movement into block C. If however there is a train in block C, track relay C becomes deenergized and its armature 9 will break away from front contact 32 resulting 10 in relay 183 being deenergized and thus displaying a danger signal. Since it is obvious that relays 182 and 183 for other blocks operate in the same manner, it is thought not necessary to describe the operation in further detail. 15 Impedance 186 is inserted in the circuit in which it is inserted to prevent the flow of alternating current through relay 182 and condenser 190 is inserted in the circuit in which it is inserted to prevent the flow of direct current through relay 183. Resistances 184 and 188 are inserted in the circuits in which they are inserted for the same purpose as resistance 113 as inserted in the cab circuit, that is to 20 reduce the flow of current through relay 28 in the dispatcher's office so that its armature 75 is not attracted to lock switch 6 unless an armature of a track relay closes a back contact 25 79 in which case a shunt circuit is established which cuts out resistances 184 and 188 thereby increasing the flow of current so as to attract armature 75 of relay 28 and lock the switch in the position it is in.

The purpose of the invention is to provide 30 a simple and inexpensive system of signaling for a railway where a track is used for both directions of traffic. It is particularly adaptable to single track uses but it is equally adapted for two or more track lines where it is desirable to use a certain track normally 35 for one direction but at times to operate trains with dispatch and safety in the opposite direction.

While in the preferred form of my invention I have shown recording means to 40 give the dispatcher knowledge of the location and progress of trains, I do not wish to be restricted to the recording means shown. Any means automatically indicating at the dispatcher's office the location and 45 progress of trains may be considered an equivalent within the scope of my invention. For instance, the perforating magnets 158 and 159 may be indication lamps which are lighted when their respective circuits are 50 closed; thus visibly indicating the location and progress of trains. Or the perforating magnets 158 and 159 may be any form of 55 electrical translating devices which indicate when the circuits through them are closed; thus the position of armature 160 in itself may be a visible indication to the dispatcher of the location and progress of trains.

60 Although I have particularly described one of the physical embodiments of my in-

vention and illustrated the same, nevertheless I desire to have it understood that the particular form illustrated is merely illustrative, and does not exhaust the possible physical embodiment of means underlying 70 the principle of my invention.

What is claimed is:

1. In a train control, and dispatching system for railways, a series of single track sections divided into blocks, a track circuit for each block, passing sidings at intervals along said trackway to permit the passage of trains, trains for operating in either direction over the single track section, a central office, sources of alternating and another kind of current at the central office, once source for giving proceed signals for one direction of train movement, and the other source for giving proceed signals for the other direction of train movement, a 80 single dispatching circuit between the said central office and each section, means at the central office for selectively supplying said currents to said dispatching circuit, signal means in said section conditioned by said currents through said dispatching circuit, and means controlled by said track circuits and said dispatching circuit to prevent changing of the direction of train movements as long as a train is in the section. 85

2. In a train control, and dispatching system for railways, a series of single track sections divided into blocks, a track circuit for each block, passing sidings at intervals along said trackway to permit the passage of trains, trains for operating in either direction over the single track section, a central office, sources of direct and another kind of current at the central office, one source for giving proceed signals for one direction of train movement, and the other source for giving proceed signals for the other direction of train movement, a single dispatching circuit between the said central office and each section, means at the central office for selectively supplying said currents to said dispatching circuits, signal means in said section conditioned by said currents through said dispatching circuit, and means controlled by said track circuits and said dispatching circuit to prevent changing of the direction of train movements as long as a train is in the section and giving an indication of the progress of the train from section to section. 105

3. In a train control, and dispatching system for railways, a series of single track sections divided into blocks, a track circuit for each block, passing sidings at intervals along said trackway to permit the passage of trains, trains for operating in either direction over the single track section, a central office, sources of alternating and direct current at the central office, one source for giving proceed signals for one direction of train move- 115 120 125 130

ment, and the other source for giving proceed signals for the other direction of train movement, a single dispatching circuit between the said central office and each section, means at the central office for selectively supplying said currents to said dispatching circuit, signal means in said section conditioned by said currents through said dispatching circuit, and means controlled by said track circuits and said dispatching circuit to prevent changing of the direction of train movements as long as a train is in the section and giving an indication of the progress of the train from section to section for each direction.

4. In a train control, and dispatching system for railways, a series of single track sections divided into blocks, a track circuit for each block, passing sidings at intervals along said trackway to permit the passage of trains, trains for operating in either direction over the single track section, proceed and stop signals for both directions of traffic, a central office, sources of alternating and another kind of current at the central office, one source for giving proceed signals for one direction of train traffic, and the other source for giving proceed signals for the other direction of train traffic, a single dispatching circuit between the said central office and each section, means at the central office for connecting either one or the source of current to the dispatching circuit, signal means in said section conditioned by said currents through said dispatching circuit, and means controlled by said track circuits and said dispatching circuit to prevent changing of the direction of train movements as long as a train is in the section.

5. In a train control and dispatching system for railways, a series of single track sections divided into blocks, a track circuit for each block, passing sidings at intervals along said trackway to permit the passage of trains, trains for operating in either direction over the single track section, proceed and stop signals for both directions of traffic, a central office, sources of direct and another kind of current at the central office, one source for giving proceed signals for one direction of train traffic, and the other source for giving proceed signals for the other direction of train traffic, a single dispatching circuit between the said central office and each section, means at said central office for connecting either one or the other source of current to the dispatching circuit, signal means in said section conditioned by said currents through said dispatching circuit, and means controlled by said track circuits and said dispatching circuit to prevent changing of the direction of train movements as long as a train is in the section, and for giving rear end protection from block to block.

6. In a train control, and dispatching sys-

tem for railways, a series of single track sections divided into blocks, a track circuit for each block, passing sidings at intervals along said trackway to permit the passage of trains, trains for operating in either direction over the single track section, proceed and stop signals for both directions of traffic, a central office, sources of alternating and direct current at the central office, one source for giving proceed signals for one direction of train traffic, and the other source for giving proceed signals for the other direction of train traffic, a single dispatching circuit between the said central office and each section, means at said central office for connecting either one or the other source of current to the dispatching circuit, signal means in said section conditioned by said currents through said dispatching circuit, and means controlled by said track circuits and said dispatching circuit to prevent changing of the direction of train movements as long as a train is in the section, for giving rear end protection from block to block, and for indicating the progress of the trains from section to section.

7. In a train control, and dispatching system for railways, a series of single track sections divided into blocks, a track circuit for each block, passing sidings at intervals along said trackway to permit the passage of trains, trains for operating in either direction over the single track section, proceed and stop signals for both directions of traffic, a central office, sources of alternating and another kind of current at the central office, one source for giving proceed signals for one direction of train traffic, and the other source for giving proceed signals for the other direction of train traffic, a single dispatching circuit between the said central office and each section, electrical switches for connecting either one or the other source of current to the dispatching circuit and means controlled by said track circuits, to prevent the operation of the electrical switches and thereby changing the direction of train movements, as long as a train is in the section, for giving rear end protection from block to block, and for indicating the progress of the trains from section to section.

8. In a train control and dispatching system for single track railways over which trains operate in either direction, a plurality of single track sections divided into blocks, a track circuit for each block, passing sidings or crossovers at intervals along said single track to permit the passage of trains, proceed and stop signalling devices along the track for either direction, the proceed signal device for one direction being controlled by alternating current, and the proceed signal device for the other direction being controlled by another kind of current, a central office, sources of alternating current and another kind of current at said central office,

manually operated means at the central office for selecting said sources of current to condition signals governing the direction of train movement over the single track section, 5 electrical circuits extending from said central office to said track for supplying said currents to said signal devices and track circuit controlled means for also controlling said signals.

10 9. In a train control and dispatching system for single track railways over which trains operate in either direction, a plurality of single track sections divided into blocks, a track circuit for each block, passing sidings or crossovers at intervals along said single track to permit the passage of trains, proceed and stop signal devices along the track for either direction, the proceed signal device for one direction being controlled by alternating current, and the proceed signal device for the other direction being controlled by direct current, a central office, sources of alternating current and another kind of current at said central offices, manually operated 15 means at the central office for selecting said sources of current to condition signals governing the direction of train movement over the single track sections, electrical circuits extending from the central office to said track 20 for supplying said currents for said signal devices, locking devices associated with said manually operated means, indicating means at the central office, and track circuit controlled means for also controlling said signal devices for providing rear end protection from block to block for locking the manually operated means in the position placed as long as a train is in the section and for indicating at said central office the location 25 of a train in relation to a track section.

30 10. In a train control and dispatching system for single track railways over which trains operate in either direction, a plurality of single track sections divided into blocks, 35 a track circuit for each block, passing sidings or crossovers at intervals along said single track to permit the passage of trains, proceed and stop signals of the fixed signal type along the trackway for either direction, 40 the proceed signal for one direction being controlled by alternating current, and the proceed signal for the other direction being controlled by another kind of current, a central office, sources of alternating current and another kind of current at said central office, 45 manually operated means at the central office for selecting said sources of current to condition signals governing the direction of train movement over the single track section, electrical circuits extending from the central office to said track for supplying said currents for said signals, locking devices associated with said manually operated means, indicating means at the central office, and track circuit controlled means for also con-

trolling said signals for providing rear end protection from block to block, for locking the manually operated means in the position placed as long as a train is in the section and for indicating at said central offices the location of a train in relation to a track section. 50

CERTIFICATE OF CORRECTION.

Patent No. 1,839,707.

Granted January 5, 1932, to

PAUL J. SIMMEN.

It is hereby certified that error appears in the printed specification of the above numbered patent requiring correction as follows: Page 8, line 129, after the word "relay" insert the letter C; page 9, line 112, claim 2, for the word "circuits" read circuit; page 10, line 32, claim 4, before "source" insert the word other; and that the said Letters Patent should be read with these corrections therein that the same may conform to the record of the case in the Patent Office.

Signed and sealed this 16th day of February, A. D. 1932.

(Seal)

**M. J. Moore,
Acting Commissioner of Patents.**
